UNITED STATES PATENT OFFICE.

PHILIP J. CANOVA, JR., AND CHARLES E. EGAN, OF CHARLESTON, WEST VIRGINIA.

FIRE-EXTINGUISHER.

1,379,850.

Specification of Letters Patent. Patented May 31, 1921.

Application filed December 17, 1919. Serial No. 345,465.

To all whom it may concern:

Be it known that we, PHILIP J. CANOVA, Jr., and CHARLES E. EGAN, citizens of the United States, residing at Charleston, in the county of Kanawha and State of West Virginia, have invented certain new and useful Improvements in Fire-Extinguishers; and we do declare the following to be a full, clear, and exact description of the invention, such as will enable others skilled in the art to which it appertains to make and use the same.

This invention relates generally to fire extinguishers and more particularly to automatic fire extinguishers.

One object of the invention is to provide a simple, cheap, and improved form of fire extinguisher construction which may be embodied in an automatic fire extinguishing sprinkling system in which no piping or other plumbing is necessary. The various automatic fire extinguishers which make up this system may therefore be placed at remote places difficult to be reached by the ordinary sprinkling systems.

Another object of the invention is to embody in automatic fire extinguishers of this character an improved form of thermostatic means for setting the device into operation.

A further object of the invention is to provide a simple and improved sprinkler construction for an automatic fire extinguisher of this character.

An additional object of the invention is to generally improve upon devices of this class by the provision of a comparatively simple, strong, durable and inexpensive construction, one which will be efficient and reliable in operation, and well adapted to the purpose for which it is designed.

With these and other objects in view, the invention consists in the novel features of construction and the combination and arrangement of parts as will be hereinafter fully described and claimed.

In the accompanying drawings in which similar reference characters designate like parts throughout the several views.

Figure 1 is a central vertical longitudinal sectional view through the plane of the trunnions of a device constructed in accordance with this invention, the device being shown in set or ineffective position.

Fig. 2 is a side elevation of the device shown in set position.

Fig. 3 is a transverse sectional view taken substantially on the line 3—3 of Fig. 1.

Fig. 4 is a view similar to Fig. 1, the device, however, being shown in its effective position.

Fig. 5 is a view similar to Fig. 2 showing the device in its effective position.

Fig. 6 is a transverse sectional view of a portion of the device taken substantially on the line 6—6 of Fig. 2, showing the position of the various elements of the thermostatic holding and releasing mechanism when in set position.

Fig. 7 is a similar view showing the mechanism in released position.

Fig. 8 is a detail vertical sectional view taken on the line 8—8 of Fig. 6.

Fig. 9 is a similar view taken substantially on line 9—9 of Fig. 6.

Fig. 10 is a detail horizontal section, taken on the line 10—10 of Fig. 2.

In the embodiment illustrated the numeral 1 designates a base having an attaching flange 2, through which securing elements 3 extend to attach the base to the ceiling C or any desired part of a building. Depending from the base 1 and secured thereto in any suitable manner, preferably by riveting, is a pair of spaced parallel and vertical arms 4, the lower ends of which are provided with threaded apertures 5 arranged in horizontal alinement with each other.

Pivottally mounted in a manner herein-after described to the lower ends of the arms 4 is a tank 6 which is closed at one end by a head 7 and provided at its other end with an opening 8. Formed integrally with the tank 6 at the edge of the opening 8 is an annular flange 9, a portion of which extends outwardly to the exterior of the tank, while another portion of it extends inwardly into the interior thereof. The outwardly extending portion of the flange 9 is externally threaded to receive a cap 10 containing a series of apertures or outlets 11.

Fixed to the cap 10 in any suitable manner and extending axially from opposite sides of the same is a short shaft or rod 12. Revolvably mounted upon the portion of the rod 12 which is disposed on the exterior of the tank 6 is a pair of sprayers 13 constructed somewhat similar to propellers or fans. The blades of one sprayer are arranged opposite in pitch or slant to the blades of the

other sprayer so that when the sprayers are acted upon by their motive agencies they will rotate in opposite directions.

Attached to the portion of the rod 12 which is disposed on the interior of the tank 6 is a number of spring arms 14. Three of such arms are shown in the present instance. These arms extend radially and downwardly from the inner free end of the rod 12 and have their lower ends inturned to form means for supporting a bottle 15 in an upright position thereon and therebetween. The mouth of the bottle contains a ball valve 16.

Arranged on diametrically opposite sides of the tank 6 intermediate of the ends thereof and secured thereto in any suitable manner are trunnions 17 having in their outer sides sockets 18, which receive the reduced unthreaded ends of screws 19 threaded in the openings 5 at the lower ends of the arms 4. This forms the means for pivoting the tank 6 to the lower ends of the arms 4. Whenever it is desired to detach the tank 25 from the arms 4, it is only necessary to remove the screws 19 when they will become disengaged from the trunnions 17.

The trunnions 17 carry spiral springs 20 attached at one end thereto in any suitable manner and provided at their other ends with hooks 21 hooked around pins 22 extending inwardly from the lower portions of the arms 4. When the tank is in the position shown in Figs. 1 and 2 of the drawings, the springs 20 are under sufficient tension to move the tank upon its pivots to an inverted or effective position, when the holding means hereinafter described is released. Obviously, when the tank is moved from the arms 4 the hooked ends of the springs 20 have to be unhooked or disengaged from the pins 22.

Pivoted upon a bracket 23 attached to the lower side of the base 1 is a lever 24. Bearing at one end against the upper edge of the lever 24 close to its pivot so as to tend to swing the lever away from the base 1 is a flat spring 25, the other end of which is securely fastened to the base 1. The free end of the lever 24 is positioned for engagement with a thermostatic stop consisting preferably of a U-shaped expandable member or bar 26 secured by means of a screw 27 to the base 1 and carrying at its other end a set screw 28. The position of the screw 28 is adjusted so that its free end will underlie the free end of the lever 24 at ordinary temperatures and hold the lever 24 in its uppermost position with the spring 25 exerting considerable pressure thereupon.

Pivoted at 29 upon a vertical axis and to the base 1 is a trigger preferably in the form of a lever 30. The lever has its free end positioned for engagement with a pin

31 or other suitable stop rising from the upper side of the lever 24 so as to hold the lever 30 with its spring 32 under tension when the lever 24 is held in the position above described by means of the thermostatic bar 26 and set screw 28 carried thereby. The spring 32 is an ordinary coil spring connected at one end to the lever 30 and at its other end to a lug or ear carried by the bracket 23. If desired, the lever 30 may be guided by a guide bracket 33.

The lever 30 adjacent its pivoted end is provided with a hook 34 which extends laterally from one edge thereof for a purpose hereinafter described.

Carried by the base 1 and extending downwardly from the same is a boss 35 having a vertical aperture therein forming a bearing for a vertical shaft 36, the upper end of which extends above the base 1 and is provided with a collar 37 or other suitable means for limiting its downward movement. The lower end of the shaft 36 extends a considerable distance below the boss 35 and is flattened as at 38. Extending laterally from the shaft 36 close to where it emerges from the boss 35 is an arm 39 having near its free end a rearwardly and upwardly extending pin or lug 40 engageable with the above mentioned hook 34. The arm 39 is also provided with a horizontally extending lug 41 to which one end of a comparatively strong coil spring 42 is connected. The other end of the coil spring 42 is connected to a post 43 depending from the base 1. The movement of the arm 39 under the tension of the spring 42 is arrested by means of a stop in the form of a post 44 also depending from the base 1.

The mechanism mounted upon the lower side of the base 1 is preferably inclosed in a protective casing or housing 45, herein shown as being made of wire screen and detachably fastened to the base by means of suitable securing elements extending through attaching ears 46 screwed to the wall of the casing. The lower side or end of the casing 45 is provided with an opening 47 to allow the flattened end 38 of the shaft 36 to pass therethrough.

Carried by the tank 6 at its end at which the opening 8 is disposed is a longitudinally extending post 48. This post is positioned upon the end of the tank 6 so that when the latter is in the upright or ineffective position indicated in Figs. 1 and 2 it will be disposed in longitudinal alignment with the shaft 36. The upper end of the post 48 is provided with a socket 49, the interior portion of which is circular in cross section, and a slot 49' is formed in the post 48 and communicates with the interior of the socket wall thereof. The flattened end 38 of the shaft 36 extends into this socket 49, and when the various parts of the mechanism

carried by the base 1 are in the positions shown in Fig. 6, the flattened end 38 of the shaft 36 extends angularly within the socket 49 so that the tank is locked in upright position thereto. The construction of the flattened end 38 of the shaft 36 and the socket 49, however, is such that when the shaft 36 is moved to its other position the flattened end 38 thereof will be disposed in alinement with the notch in the wall of the socket and the tank is then free to swing upon its pivot to an inverted position.

To limit the swinging movement of the tank 6 and to bring it to rest after it is released and has swung to its inverted position, a stop 50 is carried thereby on its wall adjacent its headed end. This stop 50 is positioned to engage one of the arms 4.

In order to sound an alarm when the device has automatically operated the other arm 4 is preferably provided with a pair of spaced contacts 51 insulatively mounted thereon and extending laterally from one edge thereof. These contacts 51 are engageable by a contact 52 fixed upon the wall of the tank. The alarm may be either a visual or an audible alarm, but for the purpose of illustration it is shown as being an electric bell 53 having one of its terminals connected by a conductor 54 insulated from arm 4 by insulating material between the spaced contacts 51. The other terminal of the bell 53 is connected by a conductor 55 to the other insulated contact 51. The conductor 55 has disposed within its length a battery or other suitable source of current 56.

The tank 6 is about three-fourths filled with a solution of sodium bicarbonate, this solution being made by placing the desired quantity of dry sodium bicarbonate in the tank and then adding the desired quantity of water, and stirring until the result has been obtained. The bottle 15 is partly filled with sulfuric acid.

The normal position of the parts of the device are shown particularly in Figs. 1, 2 and 6. From these it will be seen that the tank 6 is in an upright position and locked in this position by means of the flattened end 38 of the shaft 36 which is angularly disposed in the socket 49. The spiral springs 20 are under tension. The position of the shaft 36 is such that the arm 39 carried thereby has its post 40 engaged by the hook 34 and the spring 42 is under tension. The lever 30 is in its outermost position and held in this position under the tension of its spring 32 by the pin 31. The lever 24 is in its uppermost position under the tension of its spring 25 and held by means of the set screw 28 carried by the thermostatic bar 26. As is obvious the contact 52 is disengaged from the contacts 51.

With the parts in these positions, should a fire break out in the building in the vicin-

ity of the device or should an unusual rise in temperature take place, the thermostatic U-shaped bar 26 will expand under this increase in temperature until the free end of the set screw 28 passes from under the free end of the lever 24. The lever 24 then being released will be moved downwardly under the action of its spring 25 and the pin 31 will be thereby moved out of engagement with the lever 30. The lever 30 being freed will be moved by its spring 32 to its innermost position. This movement of the lever 30 causes a disengagement of the hook 34 from the post 40, and arm 39 thereby being freed will be swung under the tension of its spring 42 to its other position in engagement with the post 44. The shaft 36 being integrally formed with the arm 39 will be turned in its bearing and the flattened end 39 of said shaft will by this movement be positioned in alinement with the notch in the socket 49 so that the spiral springs 20 will swing the tank 6 upon its pivot to an inverted position.

When the tank 6 is in an inverted position the ball valve 16 will drop and the sulfuric acid will pass into the tank, mixing with the sodium bicarbonate and forming carbon dioxide in considerable quantity. This gas being lighter than the liquid in the tank forms in the upper end of the same and as the action of forming is so rapid considerable pressure is produced. The liquid in the tank will thereby be forced out through the openings 11 in the cap 10, and in doing so it will strike upon the sprayers 13 and rotate the latter in opposite directions. The sprayers 13 serve to spread the spray of liquid over a comparatively large area.

As hereinbefore explained the stop 50 engaging one of the arms 4 holds the tank 6 properly in inverted position.

When the tank 6 is in inverted position the contact 52 is in engagement with the contacts 51 and the circuit through the alarm device is complete so that an alarm is sounded.

After the device has been once operated the tank 6 may be refilled and the mechanism mounted upon the base 1 can be re-set. In filling the tank 6 it may be necessary to disengage it from the arms 4. Obviously this may be readily done by unhooking the free ends of the spiral springs 20 from the pins 22 carried by the arms and unscrewing the screws 19 until their reduced unthreaded ends become disengaged from the sockets 18 in the trunnions 17. The tank may be connected, after it has been filled, to the arms 4 by reversing the procedure explained.

From the foregoing description, taken in connection with the accompanying drawings, it will be seen that the objects of the invention have been effectively carried out. The

construction is particularly applicable for use in connection with a fire extinguishing sprinkling system where plumbing or piping would be difficult and impractical, as obviously no plumbing is necessary and remote places could be reached by the system.

Various changes in form, proportion, and in the minor details of construction may be resorted to without departing from the 10 spirit of the invention as defined in the appended claims.

What is claimed is:

1. In a fire extinguisher, a tank pivotally mounted for movement from an ineffective 15 position to an effective position for discharging a fire-extinguishing fluid, and means including a substantially non-fusible thermostatic detent for normally holding the tank in its non-discharging position, said 20 detent being expansible for releasing said tank upon exposure of the detent to heat of an adjacent fire.

2. In a fire extinguisher, a tank pivotally mounted for movement from an ineffective 25 position to an effective position for discharging a fire-extinguishing fluid, a shaft extending from the interior to the exterior of the tank at the discharging outlet of the tank, means on the inner portion of said 30 shaft to support a fluid container, and means on the outer portion of this shaft for spraying the fluid being discharged.

3. A device of the class described comprising a base having means for attachment 35 to a support, an arm depending from said base, a tank pivoted to said arm and being urged to inverted position, said tank containing fire extinguishing means inert when in upright position and active when in 40 inverted position, a thermostatically controlled latch mechanism mounted upon said base and including a turnably mounted shaft provided with a flattened portion, and a socket carried by said tank and receiving the 45 flattened portion of said shaft therein, one wall of said socket being provided with a cut-away portion to permit the flattened portion of said shaft to become laterally disengaged therefrom when said shaft is actuated 50 by said mechanism to dispose its flat portion in alignment with said cutaway portion of said socket.

4. A device of the class described comprising a tank containing fire extinguishing 55 means inert when in upright position and active when in inverted position to discharge fluid therefrom, the discharge of said tank being at one end thereof, a shaft extending outwardly from the discharge end 60 of said tank adjacent said discharge, and a pair of oppositely pitched rotary sprayers mounted upon said shaft opposite said discharge and adapted to be rotated in opposite directions by the fluid passing there- 65 through so as to direct said fluid in the

form of a spray over a comparatively large area, the shaft being extended into the interior of the tank and provided with spring arms and a container detachably held and clamped by said spring arms, for the purpose specified. 70

5. A mechanism of the class described comprising a base, an arm pivoted upon said base and carrying a locking member, said arm being urged to the position where said locking member is in unlocked position, a trigger engageable with said arm to hold the same with said locking member in locked position, a lever pivoted to said base and carrying means engageable with said trigger for holding the latter in set position, said lever being urged to the position where it is disengaged from said trigger, and thermostatic means for holding said lever in the position where it is engaged with said trigger. 80 85

6. A mechanism of the class described comprising a base, an arm pivoted upon said base and carrying a locking member, said arm being urged to the position where said locking member is in unlocked position, a trigger engageable with said arm to hold the same with said locking member in locked position, a lever pivoted to said base and carrying means engageable with said trigger for holding the latter in set position, said lever being urged to the position where it is disengaged from said trigger, and a U-shaped thermostatic bar fastened at one end to said base and having adjustable means at its other end for engagement with said lever to normally maintain the latter in the position where it engages and holds said trigger in set position. 90 95 100

7. A mechanism of the class described comprising a base, an arm pivoted at one end to said base and carrying a locking member, a coil spring connected at one end to said arm and at its other end to said base for urging said arm to the position where said locking member is in unlocked position, 105 a post extending laterally from said arm near the free end thereof, a trigger pivoted to said base and provided with a hook engageable with said post to hold said arm with its locking member in locked position, a coil spring connected at one end to said trigger and at its other end to said base for urging said trigger to sprung position, a lever pivotally mounted upon said base and carrying means engageable with said trigger for holding the latter in set position when said lever itself is in set position, thermostatic means for holding said lever in set position and releasing the same upon a marked rise in temperature, and a flat spring secured at one end to said base and bearing upon said lever to urge the latter to sprung position. 110 115 120 125

8. A device of the class described comprising a base having an apertured boss pro- 130

jecting from one side thereof, a shaft turn-
ably mounted in said boss and having one
end provided with locking means, an arm
extending laterally from said shaft, means
5 acting upon said arm for urging it and said
shaft to the position where said locking
means is in unlocked position, a trigger en-
gageable with said arm for holding it and
said shaft in the position where said locking

means is in locked position, means for hold- 10
ing said trigger in set position, and thermo-
static means for holding the last mentioned
means in set position but releasing the latter
upon a marked rise in temperature.

In testimony whereof we have hereunto 15
set our hands.

PHILIP J. CANOVA, JR.
CHARLES E. EGAN.
